Primary Examiner — Kendra Leslie Hamilton*Assistant Examiner* — Amanda Christensen(74) *Attorney, Agent, or Firm* — Studebaker & Brackett PC**(57) CLAIM**

The ornamental design for a wireless charging floor panel, as shown and described.

DESCRIPTION

FIG. 1 is a front, top and right side perspective view of a wireless charging floor panel, showing our new design; FIG. 2 is a rear, bottom and left side perspective view thereof;

FIG. 3 is a front view thereof;

FIG. 4 is a top view thereof;

FIG. 5 is a bottom view thereof;

FIG. 6 is a right side view thereof; and,

FIG. 7 is an enlarged sectional view taken along line 7-7 of FIG. 5 thereof.

The parts shown in the broken lines do not form part of the claimed design.
